UNITED STATES PATENT OFFICE.

ELLIOTT L. LEWIS, OF TROY, NEW YORK.

BARBED-WIRE FENCE.

SPECIFICATION forming part of Letters Patent No. 465,630, dated December 22, 1891.

Application filed June 15, 1891. Serial No. 396,274. (No model.)

To all whom it may concern:

Be it known that I, ELLIOTT L. LEWIS, of Troy, Rensselaer county, New York, have invented a new and useful Improvement in 5 Barbed-Wire Fences, of which the following is a specification.

My invention relates to that class of wire fencing which is composed of a series of links, usually barbed; and it consists in the construction of said links and their combination to form a continuous fencing.

In the accompanying drawings, Figure 1 is a plan view, and Fig. 2 is a side view, of my improved fencing. Fig. 3 is a section on the 15 line 3 3 of Fig. 1.

Similar letters of reference indicate like parts.

Each link *a b c* consists of a length of wire *A*, doubled and halved on itself to form at 20 one end of said link the eye *B*. At the opposite end of the said link the two parts *C D* of the wire are bent over to form the loop or eye *E*. The said bent-over ends *C D* are carried, one on each side of the doubled wire *A*, forming 25 the standing part of the link, and they are then bent transversely across and on the rear side of said standing part to form the barbs *F*. The said barbs are substantially parallel one to the other and are turned in opposite directions.

The manner of uniting the links is as follows: The ends *C D* of the link *b* are inserted 30 through the eye *B* of the link *a* and are then bent over the standing part of the link in the manner already described. The ends *C D* of

the link *c* are in like manner passed through the eye *B* of the link *b*, and so on. I may of course, if desired, carry the ends *C D* of one link through the eye formed by the links *c d* of the adjacent link; but in practice the arrangement above described is best employed.

This fencing is strong, durable, and easily and cheaply made.

I claim—

1. A wire-fencing link composed of a length 45 of wire doubled to form a loop or eye at one end of the link and having its extremities bent over to form a loop or eye at the opposite end of said link, the said bent-over extremities being carried rearward, one on each 50 side of the standing part of said link, and bent transversely across said standing part.

2. A wire fencing composed of a series of 55 enchain links, each link being composed of a length of wire doubled to form a loop or eye *B* at one end of the link and having its extremities *C D* bent over to form a loop or eye *E* at the opposite end of said link, the said bent-over extremities *C D* being carried rearward, one on each side of the standing part 60 *A* of said link, and bent transversely at *E* and *F* across said standing part, the eye *B* of one link engaging with the eye *E* of the next successive link, and so on, substantially as described.

ELLIOTT L. LEWIS.
